Specification for Design.

Patented May 10, 1921.

Application filed September 29, 1920. Serial No. 413,626. Term of patent 14 years.

To all whom it may concern:

Be it known that I, WILLIAM J. GREENE, a citizen of the United States, residing at Memphis, in the county of Shelby and State of Tennessee, have invented a new, original, and ornamental Design for Tire-Treads, of which the following is a specification, reference being had to the accompanying drawing, forming part thereof.

Figure 1 is a face view of a portion of a tire showing my new design.

Fig. 2 is a transverse view of the tire tread on line 2—2 of Fig. 1.

I claim:

The ornamental design for a tire tread as shown.

WM. J. GREENE.
